UNITED STATES PATENT OFFICE.

ALEXANDER McDougall, of Duluth, Minnesota.

MINING APPARATUS.

No. 823,961.

Specification of Letters Patent.

Patented June 19, 1906.

Application filed October 6, 1905. Serial No. 281,603.

To all whom it may concern:

Be it known that I, ALEXANDER McDougall, a citizen of the United States, residing at Duluth, in the county of St. Louis and State of Minnesota, have invented certain new and useful Improvements in Mining Apparatus, of which the following is a specification, reference being had therein to the accompanying drawings.

10 My invention relates to improvements in mining apparatus, and pertains more particularly to hydraulic mining-machines.

The object of my invention is to provide a machine of this character in which I provide 15 the suction end of the pipe used in mining with a rotary knife or breaker which is located in respect to the suction-pipe so that large pieces of rock, clay, and the like are either broken by the knife or breaker before 20 passing into the suction-pipe or are forced away by the same. I also provide, in combination with the rotary cutter or breaker, a strong jet of water adjacent the same, which tends to disintegrate the clay and rocks and 25 raise or suspend the same in the water, whereby the sand, clay, and stones are more readily drawn into the suction-pipe while in suspension.

Another object of my invention is to provide 30 a machine of this character which is built upon a scow of such a strength that the machine can be operated whether the scow is afloat or not, and the said scow is provided with means whereby the same may be rigidly held in any position while afloat and in operation.

In the accompanying drawings, Figure 1 is a sectional view of a mine, showing my machine therein and in which the suction-pump 40 upon the scow is forcing the ore to the dump. Fig. 2 is a sectional view of a mine of a greater depth than that shown in Fig. 1 and in which an additional pump is necessary to elevate the ore and water to dump. Fig. 3 is an enlarged side elevation of the apparatus in operation in a mine, showing the scow afloat therein.

Referring now to the drawings, 1 represents a mine in which is placed the scow 2, 50 which can either be afloat in the water 3 in the mine or could rest directly on the bottom of the mine at one side of the pit containing the water. Adjacent the mine I provide a dump 4, upon which the ore and water from the mine is dumped, and adjacent said dump 55 is a depression forming a reservoir 5, in which

flows the water from the dump, whereby the same water is used over and over again. The said reservoir is provided with a water-supply of some description, as there is a continued waste of water during the mining operation, and thus the supply for the reservoir is necessary.

My improved dredge or machine consists of a scow 2, which is made of a size to float 60 the dredge and is of such a strength as to withstand the strain to which devices of this character are subjected, whether the same is afloat or it is resting directly upon the bottom of the mine, whichever is desired, or 65 more practical in different kinds of mines or different characters of ground in which the mine is located. The said scow at each end is provided with downwardly-extending spuds 6, which are adapted to be driven into 70 the bottom of the mine and hold the scow in its set position to prevent the same from moving during the dredging operation. The scow adjacent one end is provided with a suction-pump 7, which is driven by a motor 8, 75 carried by the opposite end of the scow, and the said pump has connected thereto a flexible pipe 9, which extends downward from one end of the scow and is provided at its outer end with a metal suction-head 10, which is 80 provided on its lower face with the downwardly-extending studs 11, which extend a slight distance in the soft clay of the bottom of the mine and prevent the same from moving after it is placed in the desired position. 85 The said studs also support the casing-head 90 ing a short distance above the bottom of the mine, as will be hereinafter more fully described. The outer end of the casing-head 10 is open, and through which the ore, clay, 95 and sand is drawn to the suction-pump, as will be hereinafter more fully described.

The end of the scow carrying the pump is provided with an upwardly and outwardly extending derrick 13, which is pivotally 100 mounted on the scow, the purpose of which will be hereinafter more fully described. The outer end of said derrick is provided with a block and tackle 14, the lower end of which is detachably secured to the suction-head 10 105 and by means of which the same is raised and lowered during the movement of the scow within the mine. The head 10 adjacent its outer end is provided with an upwardly-extending elongated lug 15, in which is rotatably mounted the shaft 16, which is provided on its end with a rotary cutter or breaker 17,

which, as shown, rotates close to the outer open end of the suction-head 10, and thus prevents large pieces of ore from passing into the pipe 9 and choking the same. The said 5 knife or cutter 17, as shown, is in the form of a propeller, which not only cuts or breaks the large pieces of clay and rock from the end of the head 10, but also aids in causing the broken stone, &c., to travel upward through 10 the hose 9. While I have shown and described the blade 17 in the form of a propeller, it will be understood that the same could be of any other form and the form being governed by the character of clay or ore 15 in which the same is to be used. The shaft 16 extends inward and is provided with a universal connection 18, with a shaft 19 carried by the scow, and thus the said propeller is rotated, no matter in what position the suction- 20 head 10 is located. The shaft 19 is driven by any desired means, such as an independent motor, or may be driven by the motor 8, which drives the suction-pump.

The suction-pump 7 is provided with a discharge-pipe 20, which has connected thereto the upwardly-extending flexible pipe 21, which extends out of the mine to the dump and through which the ore and water are conveyed to the dump. In Fig. 1 the pump is of 25 sufficient power to raise the water and ore to the dump; but when the mine has become too deep the power of the suction-pump 8 is not sufficient to raise the ore and water to the dump, and in such a case an intermediate 30 force-pump 22 is used to force the water up to the dump. When the mine has become still deeper, two or more of these force-pumps 35 22 are arranged in tandem.

In order to supply the mine with the necessary water, I provide a suction-pipe 23, which extends into the reservoir 5, and the opposite end of said pipe is connected to a suction-pump 24, which has a discharge-pipe 25 extending down into the mine. The lower 40 end 25' is carried by the framework of the scow and has connected thereto a flexible pipe 26, which extends down into the water adjacent the casing-head and is provided with a nozzle 27, which discharges the water at one 45 side and adjacent the casing-head, and the force of the water disintegrates the sand, clay, and ore and causes the same to be suspended in the water, whereby the suction of the pump 7 draws them within the pipe 9. 50 The said nozzle 27 has connected thereto a block and tackle 28, which is also connected to the upper end of the derrick 13, and whereby the same may be raised and lowered when the suction-head is lowered, whereby the water 55 from the nozzle is working on the bottom of the mine adjacent the casing-head.

Having thus described my invention, what I claim, and desire to secure by Letters Patent, is—

65 1. A mining apparatus, comprising a scow

having a suction-pipe extending below the same, a rotary breaker adjacent the end of said pipe, a water-reservoir adjacent the scow, a pipe leading from the water-reservoir adjacent the end of the suction-pipe, and 70 a pipe leading from the suction-pump to a dump.

2. A mining apparatus, comprising a scow having a suction-pipe extending below the same, a suction-head carried by the end of 75 said pipe, a rotary breaker carried by the suction-head, a water-reservoir adjacent the scow and a pipe leading from the reservoir and discharging water adjacent said breaker.

3. A mining apparatus, comprising a scow, 80 a suction-pump thereon, a suction-pipe carried by the pump and extending downward over one end of the scow, a discharge-pipe extending from the pump, a suction-head carried by the end of the suction-pipe, a rotary breaker carried by the suction-head and a water-supply pipe discharging adjacent the 85 rotary breaker.

4. A mining apparatus, comprising a scow, a suction-pump thereon, a suction-pipe carried by the pump and extending downward over one end of the scow, a discharge-pipe 90 extending from the pump, a rotary cutter carried by the lower end of the suction-pipe, a water-supply pipe discharging water adjacent the rotary breaker, a derrick carried by the scow, and a block-and-tackle connection 95 between the derrick and the flexible pipe and the water-supply pipe.

5. A mining apparatus, comprising a scow, 100 means for holding the scow in any desired position, a suction-pump carried by the scow, a flexible pipe extending from the pump below the scow, a rotary breaker carried by the end 105 of said flexible pipe, a pipe discharging water adjacent the said rotary breaker, a pipe leading from the pump to the top of the mine and pumps arranged in tandem in said pipe-line.

6. A mining apparatus, comprising a scow, 110 means for holding the scow in any desired position, a suction-pump carried by the scow, a flexible pipe extending from the pump below the scow, a rotary breaker carried by the end of said flexible pipe, a pipe discharging water adjacent the said rotary 115 breaker, a pipe leading from the pump to the top of the mine and pumps arranged in said pipe-line in tandem between the scow and the top of the mine at specified distances.

7. A mining apparatus, comprising a scow, 120 means for holding the scow in any desired position, a suction-pump carried by the scow, a flexible pipe extending from the pump below the scow, a suction-head carried by the outer end of said flexible pipe, a rotary breaker carried by the outer end of said head, a water-supply pipe discharging water adjacent the 125 said rotary cutter, a derrick carried by the scow, a block-and-tackle connection between said supply and flexible pipes and the derrick 130

for raising the same, a discharge-pipe connected to the pump and extending to the top of the mine, and pumps arranged in tandem in said discharge-pipe.

- 5 8. A mining apparatus, comprising a scow, a suction-pump upon said scow, a discharge-pipe leading from the scow to a dump outside the mine, pumps arranged in tandem in said discharge-pipe, a reservoir adjacent the
10 dump and adapted to receive the water from the dump, a suction-head carried by the suction-pipe below the scow, a rotary breaker carried by the outer end of said head, a motor

carried by the scow for operating the pump and the breaker, a pump adjacent the reservoir and having a pipe leading into the mine adjacent the breaker, a derrick carried by the scow, and a block-and-tackle connection between the water-supply pipe and the suction-pipe and the end of the derrick.

In testimony whereof I affix my signature in presence of two witnesses.

ALEXANDER McDougall.
